CLAIM

The ornamental design for a vehicle tail lamp, as shown and described.

DESCRIPTION

FIG. 1 is a top front perspective view of a left vehicle tail lamp (the right vehicle tail lamp being a mirror image, and is not shown);

FIG. 2 is a bottom front perspective view thereof;

FIG. 3 is a top rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.
